(57) CLAIM

The ornamental design for a hairdresser's cape, as shown and described.

DESCRIPTION

FIG. 1 is a top plan view of a hairdresser's cape showing my new design, shown in open condition; and

FIG. 2 is a front perspective view thereof, shown in use; and,

FIG. 3 is a rear elevation view thereof. The two squares represent attachment means for a back scarf to be added.

The broken lines shown in the drawings are for illustrative purposes only, and form no part of the claimed design.
